UNITED STATES PATENT OFFICE.

GEORGE H. TOWNSEND, OF GREENWICH, CONNECTICUT.

DESIGN FOR A MOTOR-HEAT-INDICATING INSTRUMENT.

Application filed June 15, 1927. Serial No. 22,444. Term of patent 14 years.

To all whom it may concern:

Be it known that I, GEORGE H. TOWNSEND, a citizen of the United States, residing in Greenwich, county of Fairfield, and State of Connecticut, have invented a new, original, and ornamental Design for Motor-Heat-Indicating Instruments, of which the following is a specification, reference being had to the accompanying drawing, forming a part thereof.

Figure 1 is a front elevation of a motor heat indicating instrument showing my new design;

Figure 2 is a side elevation of the instrument; and

Figure 3 is a rear elevation of the instrument.

The salient feature of the invention resides in providing a face of the instrument with the leaf or wreath design as shown.

I claim:

The ornamental design for a motor heat indicating instrument as shown and described.

GEORGE H. TOWNSEND.
